1 Claim. (Cl. 253—67)

1

The invention relates to a device for starting the rotor of a steam turbine using steam passages instead of blades.

By the known types of steam turbines generally the steam is first let into guide blades (nozzles) at the one end of the rotor to obtain the right direction and speed. The steam jets then go through the blade rim of the runner that is located behind the blade rim to leave that runner in nearly opposite direction. When the steam has still sufficient velocity or pressure, it can go through a second rim of guide blades (nozzles) to be led into the right direction, respectively to reassume its original velocity by its expansion, in which way this can again be led through the blade rim of a second runner that is located behind the blade rim, which runner is placed, like the first one, immovably on the same axle. In that way a great number of guide blades and runners can be placed behind each other if only the steam contains sufficient heat contents. The pressure against the blades of the runners causes a great coupling that sets the axle revolving. The function of the guide blades (nozzles) is evident, the steam every time escapes from the runners in the wrong direction, approximately opposite to their movement and the guide blades (nozzles) alter the wrong direction into the right one.

The disadvantages which are inherent in such types are the great losses of power caused by the friction of the steam between the guide and running blades, the collisions against the sharp edges of the blades, the formation of whirlpools and whirls, the so-called wheel friction caused by the turning of the turbine-runners in the steam, while always the steam is flowing at the exterior round the runners, without exerting any energy.

According to the invention these disadvantages are wholly eliminated, so that an important technical effect is obtained.

In the accompanying drawings constructions according to the invention are schematically shown, by way of example.

Fig. 1 shows a longitudinal section of a turbine according to the invention, in which the steam goes in two directions through the rotor.

Fig. 2 is a section on the line A—B on Fig. 1.

Fig. 3 shows the steam pressure and velocity diagram.

Fig. 4 is a longitudinal section of a turbine in which the rotor has been constructed in a slightly different way.

Fig. 5 shows a longitudinal section of a turbine according to the invention in which the steam passes in one direction through the rotor.

2

Figs. 6, 7, and 8 show other constructions of the turbine.

Fig. 9 is the steam pressure and steam velocity diagram of the turbine of Fig. 8.

Fig. 10 shows a section on the line C—D of Fig. 8.

Fig. 11 shows an outer circumference of a sleeve with a broad groove.

Fig. 12 shows a construction of the turbine with three jet pipes.

In Fig. 1 the frame is represented by 1 and the rotor by 2, which consists of a cylinder or drum, shrunk round an axle 3, that rests in bearings 4, and two sleeves 8 and 9.

The drum of the rotor 2 has a peripheral groove in the middle, which groove is indicated by number 5. From this groove 5 grooves 6 run left and right across each half of the drum, respectively, bordered by a small wire 7. These grooves 6,

which run to the ends of the drum, are gradually cut deeper. From each end of the drum the sleeves 8 and 9, respectively, extend to the peripheral groove 5. In this way the grooves 6 become helicoidal steam passages which begin at

5 and through which the steam can escape at the ends. The inlet of the steam is, consequently, at

5. The sleeves, 8 and 9 must be suitably fixed immovably around the drum; the rotor must be able to rotate steam-tight in the turbine frame

10. Through one or more jet pipes 10 (see Fig. 2) the steam flows with great speed into the groove

5 and into the helicoidal passages 6, in which the resistance is increased by the friction resulting in the release of energy, which sets the rotor

20 revolving. In a straight pipe a gas or steam meets resistance, which increases with the velocity. This resistance is greatly increased in curves.

In the turbine according to the invention the passages are a series of circular curves placed

25 behind each other. Instead of the helicoidal grooves in the drum of the rotor 2, these grooves could be cut in the sleeves 8 and 9, as shown in

Figs. 6 and 7, or both the drum and sleeves 8 and 9 could be provided with helicoidal grooves 6, as

30 shown in Fig. 8. In the last case care should be taken that by the fitting the grooves of the drum and those of the sleeves are put exactly opposite each other, so that on each half of the drum one steam passage is formed. By the construction

35 of steam turbines of a greater axial length a greater number of adjoining steam passages, all with a similar bearing, can be fitted instead

40 of one steam passage on each half of the drum. In this connection for larger units more rotors

45 could be mounted on one axle (see Fig. 8). By

50

55

construction of steam turbines of a greater axial length a greater number of adjoining steam passages, all with a similar bearing, can be fitted instead

of one steam passage on each half of the drum. In this connection for larger units more rotors

55 could be mounted on one axle (see Fig. 8). By

the construction of two rotors on one axle the escape of steam can take place at the ends and in the center of the turbine frame. The inlet is as with the first described, in the center of each rotor. Without any objection the steam could be profitably used in a high-pressure and then in a low-pressure turbine.

The construction could be simplified, by the system, by making one end of the drum thicker, which end should be able to move freely and steam tight in the turbine frame as shown at 14 (see Fig. 5). At the inner side of the thick part the drum has a peripheral groove 5, and from groove 5 the helicoidal groove 6 begins which, as is the case with the former, is gradually cut deeper to its end. Over the drum a sleeve is fitted to groove 5, which sleeve is immovable on the drum. Also this rotor, shaped in this way, should revolve steam tight in the turbine frame. The steam is let into the groove 5 by means of one or more jet pipes. The exhaust steam at the ends of the rotor must be mutually combined to neutralise axial differences of pressure. All these combinations are, however, variants on the first-described systems and under the same principles.

The invented turbine system offers many advantages: the steam can be led through converging jet pipes with a certain velocity and under a certain pressure into the groove 5. By the correctly defined mutual relations between jet pipes, the groove 5, the length and the diverging positions of the steam passages, it is possible to make the steam produce energy in the steam passages by which the steam-velocity through 35 gradual expansion to the final pressure can be kept constant. See the diagram of the steam pressure and the steam velocity (Fig. 3). In this figure the line of steam pressure is shown by 11, that of the velocity by 12, while line 13 shows the path of the condensator-pressure. Experiments will have to show in which way the grooves in the rotor must be made to allow the greatest possible efficiency. With regard to the question of the steam tight revolving of the rotor in the turbine frame it may be observed that this can be effected without much difficulty in the case of small turbines by providing the sleeves at the outer circumference with broad grooves, while in big rotors the well known so-called labyrinth-packing 18 (see Fig. 11) would be suitable.

Especial because of its simplicity such a turbine offers great advantages, by keeping the production-costs as low as possible. Another advantage lies in the fact that by the construction according to the invention the steam jet is hardly subject to any alteration of the direction of the flow, as is the case with the known types of turbines.

Fig. 4 shows a construction similar to the other figures, with only this difference that the sleeves 8 and 9 are bent inwardly at their ends 17 with concentric openings for the steam exhaust. This will result in the steam-exhaust taking another direction. Dependent on the admissible friction the bending is greater or smaller. The working

development can also take place by allowing the steam to expand in diverging jet pipes from the initial pressure to the final pressure. Then the steam flows with the greatest possible velocity into the groove 5 and into the steam passages 6, in which emission of energy takes place till the velocity of the steam is sufficiently exhausted. When the sleeves 8 and 9 are shrunk in the right way on the drum, leakage in the steam passages is prevented. By making use of a greater number of jet pipes (Fig. 12) the groove 5 can be made smaller, so that the frictional loss at the small inner wall of the turbine frame can be reduced to a minimum. When the steam has come in the steam passages in which it can, gradually and without shock, release kinetic energy, the force which is accumulated in it can be, without any loss, transferred to the rotor, which result cannot be produced in any other of the known steam turbines, in which the efficiency is considerably reduced by losses caused by steam friction against the guide and the moving blades which must be polished with great care. The causes of the several losses of power have been explained already in the beginning of the description. In the turbine which is described in this application, it is merely the friction of the steam in the steam passages which sets the rotor revolving. By all these propitious conditions it is possible to build, within normal scope, high speed and low speed steam turbines of high efficiency. As a result of the limited number of sub-parts which can be easily produced, the rotor can be made very light and yet very strong and especially cheap. Where the weight of the rotor can be kept small the losses caused by the lower friction are consequently also very small. In case of defects in the bearings the rotor is not damaged, because of the absence of blades. The rotor is substantially indestructible by use.

The rotor forms a stable and strong unit so that the critical number of revolutions can be, even at high speed, above the working capacity. By acceleration of the revolutions, the critical number of revolutions is never exceeded so long as the axle does not experience undue flexing.

In conclusion it may be stated that, when instead of steam, air or liquid is forced with great velocity through the passages the rotor can also be set revolving.

The turbine needs not be restricted to the described constructions, but may be altered in many ways within the scope of the invention.

What I claim is:

55 In a turbine, the combination of a hollow frame provided with bearings and fluid ports; a shaft rotatable in said bearings; two rotors mounted upon said shaft, and having spiral channels extending thereabout and opening toward said ports; and a sleeve cover mounted upon each rotor and covering said channels, the ends of the covers adjacent the ends of the frame being bent inwardly toward said shaft.

65 ALEX FREDERIK GEORGE GLASER.
